UNITED STATES PATENT OFFICE

JOSEPH D. BELL, OF SAN FRANCISCO, CALIFORNIA

ELEVATED TRANSPORTATION SYSTEM

Application filed January 30, 1928. Serial No. 250,434.

This invention relates particularly to an elevated transportation system.

An object of the invention is to provide a transportation system of the elevated type wherein the carrying conveyances are suspended from, and apply tractive effort to an overhead rail, in conjunction with means for maintaining the conveyance in a state of stable equilibrium.

10 A further object of the invention is to provide a mono-rail transportation system arranged above the car and from which the car is suspended, together with a rail beneath the car and in alignment with the overhead rail, 15 to maintain the said car in a predetermined operating position.

A still further object of the invention is to provide a passenger carrying car for a transportation system having individual 20 platforms thereon to support the passengers being conveyed, in conjunction with means to move said platforms, together with the passengers thereon, in and about the interior of the car to promote quick filling or discharging 25 of the passengers from the said car.

Another object of the invention is to provide means for directing the movement of an endless belt having platforms thereon around an enclosure where it may be desired to display articles placed upon the several platforms, such, for example, as furniture, or other merchandise, each platform carrying a full load of material artistically arranged for suitable display to the public at one particular place whereby one show window can be made to give an adequate display continuously changing of a number of the loaded platforms.

40 Other objects of the invention are to provide a mono-rail system of transportation consisting of a pair of suspended tracks arranged in spaced relation, on and between which a conveyance is movably guided, with means on the conveyance to move the passengers at will, into any selected location within the car, or relative to the doors in said car, to hasten the filling or discharging of passengers from the car.

45 In this specification and the annexed drawings, the invention is illustrated in the form

considered to be the best, but it is to be understood that the invention is not limited to such form, because it may be embodied in other forms; and it is also to be understood that in and by the claims following the description, it is desired to cover the invention in whatsoever form it may be embodied.

55 In the accompanying two sheets of drawings:

Fig. 1 represents a plan view of a car suspended on a rail constructed in accordance with my invention.

60 Fig. 2 is a side elevation of Fig. 1.

Fig. 3 is a plan section taken through a passenger conveyance constructed in accordance with my invention, taken on the line 3—3 of Fig. 4.

65 Fig. 4 is a vertical section through my car taken on the line 4—4 of Fig. 3, the means for guiding the car in a vertical position on the lower rail being a modified form of the apparatus for accomplishing this function.

70 Fig. 5 is a fragmentary cross section taken through Fig. 2 on the line 5—5, showing the preferred manner of guiding the car on the lower rail.

75 The construction illustrated in the drawings comprises the upper traction rail 1 and lower guide rails 2 arranged in spaced, suspended relation above the ground. As shown in Fig. 4, the upper rail is supported on a bracket 3 which is connected by suitable supports 4 to a pillar or column, or other equivalent structure, for supporting said rail in suspension, the lower rail also being supported in a suitable manner. My method of suspending rails in spaced relation above the ground is to provide an elevated transportation system which will differ materially from the conventional type of elevated rail systems now in use.

80 85 90 95 100 My invention contemplates particularly the supporting of the passenger carrying conveyance by the rails 1 and 2 arranged above and below the car, to reduce to a minimum, the amount of space required for a complete operative transportation system, as contrasted with the conventional type of broad gage elevated railways. In my system I provide rapid transportation by ac-

commodating the passengers in the cars capable of holding ten or twelve individuals, in a standing position, whereby it is possible to make the cars of relatively narrow width and of short length and, at the same time, to run the car at a speed varying from thirty to sixty miles an hour. The passengers are obliged to stand and in consideration thereof to be carried at a rapid rate of speed to their destinations, in contrast with present day method of slow transportation where seats are provided to make comfortable the wait of the passenger, while being transported from one point to another.

Each of my cars or conveyances 5 consist of a substantially rectangular structure that is suitably rounded at its front and rear ends 6 and 7 to minimize wind resistance, and which, on the roof 7' thereof, is provided adjacent its front and rear ends with standards 8 and 9, each standard having a bearing 10 thereon, that extends over the upper rail 1, substantially parallel thereto. A wheel 12 is journaled in each of the bearings 10, the wheel adjacent the front end of the car being a traction wheel and having a sprocket 13 on an end thereof that is driven by a chain 14 running off of the motor 15, arranged within the car housing. The car is also provided with rollers 16 and 17, journaled on the roof thereof, to engage opposite sides of the rail 1 for the purpose of holding the car wheels 12 in proper running position on the rail 1. Although I have shown a particular type of car wheel 12, together with a rail 2 for maintaining said wheels 12 on the track, it is to be understood that the invention contemplates the use of a modified form of track and wheel structure.

The motorman or operator in charge of the car stands at the forward end of the car adjacent the controller box 18, having a suitable control means thereon for stopping and starting the motor, it being contemplated that the motor 15 is to be driven by electricity carried to the car by an overhead wire 19.

The guide rail 2 beneath the car is substantially U-shaped in cross section, the open side of the channel facing the bottom of the car. A wheel 20 is journaled in the car midway of the ends thereof, said wheel being confined to run in the groove in the lower rail 2. The wheel 20 is rotatably journaled in bearings 21 and 22, each of which are slidably mounted in guides 23 arranged on opposite sides of the said wheel, within the interior of the bottom of the car, and expansion springs 24 are interposed between the guides 23 and bearings 21 and 22 to permit either the wheel or car to have a free vertical reciprocal movement.

A flooring 25 is arranged adjacent the bottom of the car in spaced relation therewith, said flooring being provided with a continu-

ous symmetrical slot 26 cut therethrough that substantially parallels the outer contour of the car. A plurality of individual platforms 27 are arranged within the car and each platform has a shaft 28 that extends from the under side thereof through the slot 26 in the flooring. The lower end of each shaft is provided with a roller 29 journaled thereon, and all of said shafts 28 are connected together below the flooring by an endless belt or chain 30. At opposite ends of the car between the flooring and bottom thereof, a pair of sprocket wheels 31 and 32 are journaled to mesh with the endless chain 30 and to impart directional movement to said chain. It is obvious that movement of the chain will cause the shaft rollers 29 to move on the bottom of the car in a path corresponding to that of the slot 26 in the flooring, and that the individual platforms will be moved in unison over the flooring. The passengers upon entering through the doors in the car at a station, step onto one of the individual platforms 27, and through the manipulation of the car operator, the platforms 27 will be advanced around the interior of the car. In the same manner, the platforms with the passengers thereon, can be moved relative to the doors to effect the quick discharge of passengers from the conveyance.

A rod 34 is secured in a vertical position to each platform 27 to afford a hand grip for the passenger on each platform, and each rod 34 moves with its platform, as the platform is advanced around the car. The lower end 37 of each of the rods 34 extends through a slot 38 formed in the said flooring 25 parallel to the slot 26. An elliptical guideway 42 that complements the slots 26 and 38 is provided on the under side of the flooring between the slots 26 and 38 to maintain the passenger platforms 27 in a predetermined position on the flooring, and to prevent lateral or disaligning movement thereof. A roller 43 is journaled on the lower end of each rod 34 and is confined in the guideway 42 to properly center the rods within the car as aforesaid.

The upper end 44 of each rod 34 is provided with a roller 43' journaled thereon, and guided in a track 45 suspended from the under side of the roof of the car. The upper track 45 follows the same contour as the guideway 42 on the flooring of the car so that the support rods 34 are maintained in a true vertical position when being advanced around the conveyance. A chain 46 that is driven by the motor 15 is connected to the shaft on which the sprockets 31 and 32 are mounted, whereby the car operator can actuate said sprockets as desired, to move any selected platform or platforms 27, relative to the entrance or exit doors 47, to take on or discharge passengers.

In Fig. 4, the under side of the car is provided with a pair of spaced rollers 48 journaled thereon to engage the opposite face of

the lower track 49, and to keep the car on the track in substantially the same manner as the preferred form of car centering means shown in Fig. 5.

Having thus described this invention, what I claim and desire to secure by Letters Patent is:

1. An enclosure having a continuous trackway on the flooring thereof; a plurality of individual platforms arranged on the flooring to move in the trackway; a hand grip on each platform; and means to move all of the platforms around the trackway.

2. An inclosure having a continuous trackway on the flooring thereof; a plurality of individual platforms arranged on the flooring to move in the trackway; a hand grip on each platform; a trackway for each hand grip arranged parallel to the first mentioned trackway to maintain each hand grip and platform in a selected position within the interior of the enclosure; and means to move all of the platforms around the trackway.

3. An inclosure having a continuous trackway on the flooring thereof; a plurality of individual platforms arranged on the flooring to move in the trackway; a hand grip on each platform; a pair of trackways arranged parallel to the first mentioned trackway to confine each of the opposite ends of the hand grip therein and to maintain each hand grip and platform in a selected position within the interior of the enclosure; and means to move all of the platforms around the trackway.

4. A housing comprised of top, bottom, side and end walls; a flooring adjacent the bottom having a continuous slot therein substantially parallel to the side and end walls of the housing; a plurality of individual carrier platforms arranged to move over the flooring, each platform having a guide therein confined in the slot; a trackway on the flooring arranged parallel to the slot; a complementary trackway on the top wall of the housing; a vertically disposed rod on each platform having each of its opposite ends movably related to one of the trackways; and means to move each of the platforms and rods in unison around the interior of the housing.

5. A housing comprised of top, bottom, side and end walls; a flooring adjacent the bottom having a continuous slot therein substantially parallel to the side and end walls of the housing; a plurality of individual carrier platforms arranged to move over the flooring of the housing, each platform having a guide therein confined in the slot; a platform supporting roller on the lower end of each guide to roll on the bottom wall of the housing; an endless chain connecting all the guides; a trackway on the flooring arranged parallel to the slot; a complementary track-

way on the top wall of the housing; a vertically disposed rod on each platform having each of its opposite ends movably related to one of the trackways; and means to move each of the platforms and rods in unison around the interior of the housing.

In testimony whereof, I have hereunto set my hand at San Francisco, California, this 29th day of December, 1927.
